CLAIM

The ornamental design for a rocker switch as shown and described.

DESCRIPTION

FIG. 1 is a perspective view of a rocker switch showing my new design;

FIG. 2 is a front elevation view thereof; and the rear elevation views is identical;

FIG. 3 is a left elevation side view thereof;

FIG. 4 is a right elevation side view thereof;

FIG. 5 is a top plan view thereof;

FIG. 6 is a bottom plan view thereof; and

FIG. 7 is a practical application view thereof on a rocker switch at off status; and,

FIG. 8 is a front elevation view at off status.

The broken lines showing in the drawings are for the purpose of illustrating portions of the switch and form no part of the claimed design, and the dot-dash lines are for the purpose of confirming the boundary of the scope.
